GEORGE L. PIERCE, OF BROOKLYN, NEW YORK, ASSIGNOR TO A. G. SPALDING & BROS., OF NEW YORK, N. Y., A CORPORATION OF NEW JERSEY

SHOE CLEAT

Application filed October 8, 1929. Serial No. 398,120.

My invention relates to detachable cleat structures for athletic or sport shoes.

The invention provides a cleat consisting essentially of two parts: a base in the form of a screw socket permanently secured, usually by nailing, to the sole or preferably the outsole of the shoe, and a cleat proper including a body which may be of moldable plastic material such as vulcanite, fibre, hard rubber, or other suitable material, and a threaded head which is screwed into the socket and retains the cleat firmly in position while in use, but permits easy removal for replacement, merely by unscrewing it. In preferred cases, the threaded cleat head is a separate metal piece which has a part or stem embedded in the molded body. Preferably, also, the central part of the socket, within the threaded sleeve, is of moderate thickness and 20 externally convex, so that when the cleat is screwed in, its head end engages and distorts or flattens the convex portion of the socket, thus producing resilient forcible pressure between the socket and the cleat and the 25 screw threads, which additionally prevents unscrewing until the cleat is intentionally removed.

The accompanying drawing shows one representative embodiment of the invention. After considering this example, skilled persons will understand that variations may be made within the limits defined by the claim.

Fig. 1 is a bottom plan of a sport shoe, having a suitable plurality of the cleat structures applied to the sole and heel thereof.

Fig. 2 is a section at 2—2, Fig. 1, showing one of the cleats in side elevation and another in vertical section.

Fig. 3 is a perspective view of the socket. Fig. 4 is a perspective view of the cleat proper, removed from the socket.

The socket, as best shown in Figs. 2 and 3, is of metal, comprising a cylindrical or sleeve portion 1 having an internal screw-thread 2 extending from a flange 3, which has a suitable plurality of perforations 4 for insertion of fastening devices. Preferably, the central or bottom portion 5 of the socket, at the inward end of sleeve 1, is of moderate thickness and of dished or convex form, the convexity

being outward, or toward the open end of the sleeve. Any suitable number of the sockets are secured to the shoe sole in any suitable way, conveniently by nailing; and as shown in Fig. 1, the fastening nails or brads 6 may 55 be driven only through the outsole 7 and clinched thereon so that they do not pass through to the insole or lining.

The cleat proper, shown separately in Fig. 4, usually includes an outer or spike portion 8 and an upper or head portion 9 of smaller diameter than the upper end of the spike portion, and externally threaded as at 10, this threaded head being engagable in the threaded socket sleeve. While the cleat proper may 60 in some cases be in a single piece and either of a moldable plastic or of metal, in many cases it is preferred to make it in two pieces. Thus, as specifically shown, the part 8 referred to above as the spike portion may be 65 separate from the head portion 9. In such cases, the spike portion 8 is conveniently referred to as the cleat body, and may be of any suitable moldable plastic material such as 70 fibre, vulcanite, hard rubber, etc. The head portion will then be of metal, including the threaded portion 10 to engage in the socket sleeve, and a stem 11 about which the body 8 is molded. The metal head may also include 75 a flange 12 overlying the inward end of the molded body and engaging against the outer end of the socket sleeve 1; otherwise this flange may be omitted and the molded material may then engage directly with the 80 outer end of the socket sleeve, when the cleat is screwed into position.

When the cleat proper is screwed into the socket, as shown in Fig. 2, the inner end of the head 9 engages the convex central portion 90 5 of the socket and depresses or flattens that portion until the flange 12 is in engagement with the outer end of the socket sleeve. The deformed central portion of the socket then exerts resilient pressure and friction upon 95 the inner end of the cleat head and also produces active resilient engagement of the cleat threads with those of the socket, so that inadvertent unscrewing of the cleat while in use is practically impossible, but it may easily 100

be unscrewed when desired, as for replacement when damaged or worn.

The external shape of the cleat proper or of its molded portion 8 may vary. The generally tapered or conical form shown is preferred in many cases.

I claim:

A detachable cleat structure for athletic or sport shoes, comprising a socket and a cleat proper, the socket having an internally threaded sleeve projecting from a flange perforated for insertion of attachment devices, and the cleat including a body and a head portion externally screw-threaded to engage in the sleeve thread, the socket at the inner end of the sleeve being of moderate thickness and externally convex, this portion being deformed by insertion of the cleat head and thereupon exerting resilient pressure on the head and screw-threads, preventing inadvertent unscrewing.

In testimony whereof I affix my signature.
GEORGE L. PIERCE.
